GEAR PUMP

John Dolza, Davisburg, Earl W. Rohrbacher, Detroit, and John Zimmerman, Grosse Pointe Woods, Mich., assignors to General Motors Corporation, Detroit, Mich., a corporation of Delaware

Application August 11, 1951, Serial No. 241,432

10

6 Claims. (Cl. 103—126)

This invention relates to gear pumps suitable for use in liquid-pressure systems, for example, the burner fuel system of an internal combustion turbine.

An object of the present invention is to provide a gear pump of compact and durable construction capable of pressurizing a liquid to a relatively high pressure. In the disclosed embodiment thereof, the object is accomplished by subjecting the gear shafts to forces obtained by pressure fluid which practically balance-out the forces to which the shafts are subjected due to gear-tooth loading and hydraulic loading of the pump. These balancing forces are applied through the use of pressure pockets adjacent to the shafts. Each gear shaft has two cylindrical portions between which a pump gear is located. Each cylinder is received by a sleeve having internal longitudinal grooves which are separated by sealing segments which fit the cylinders with close clearance. The pockets which these grooves provide are connected with the pump that they receive fluid under different pressures. The effective area of the pockets, the location of the pockets and the fluid pressure in the pockets are such that the required balancing effect is obtained. Because the shaft bearings are practically free of forces due to gear-tooth loading and hydraulic loading of the pump, they can be relatively small in diameter and the pump shafts can be relatively closely spaced. Therefore a gear pump which is compact and durable in construction and which is capable of pressurizing liquid to a relatively high pressure can be provided.

Further objects and advantages of the present invention will be apparent from the following description, reference being had to the accompanying drawings, wherein a preferred embodiment of the present invention is clearly shown.

In the drawings:

Fig. 1 is a longitudinal sectional view on line 1—1 of Fig. 4.

Fig. 1A is an enlarged fragmentary view showing the attachment of a pump screen to a mounting ring.

Fig. 1B is an enlarged fragmentary view of one of the shaft seals.

Fig. 2 is a sectional view on line 2—2 of Fig. 1.

Figs. 3 and 4 are, respectively, sectional views on lines 3—3 and 4—4 of Fig. 1.

Fig. 5 is a fragmentary, sectional view on lines 5—5 of Figs. 3 and 4.

Fig. 6 is a fragmentary, sectional view on line 6—6 of Fig. 3.

Fig. 7 is a fragmentary, sectional view on lines 7—7 of Figs. 3 and 4.

Fig. 8 is a fragmentary, sectional view on line 8—8 of Fig. 4.

Fig. 9 is a sectional view on line 9—9—9 of Fig. 3.

Figs. 10 and 11, respectively, are sectional views on lines 10—10 and 11—11 of Fig. 1.

Figs. 12 and 13 are, respectively, sectional views on lines 12—12 and 13—13 of Fig. 2.

2

Figs. 14 and 15 are respectively, sectional views on lines 14—14 and 15—15 of Fig. 1.

Figs. 16 and 17 are, respectively, sectional views on lines 16—16 and 17—17 of Fig. 14.

Fig. 18 is an enlarged fragmentary, longitudinal sectional view showing a shaft and a sleeve which provides sealing segments between pressure pockets.

Fig. 19 is a sectional view on line 19—19 of Fig. 1.

Fig. 20 is a sectional view on line 20—20 of Fig. 19.

Fig. 21 is an enlarged end view of a drive shaft pocket sleeve.

Fig. 22 is a sectional view on line 22—22 of Fig. 21.

Fig. 23 is an end view of a driven shaft pocket sleeve.

Fig. 24 is a sectional view on line 24—24 of Fig. 23.

Fig. 25 is a side view of the pump.

Referring to Fig. 1, the pump enclosure comprises a front bearing housing 30f, a plate 31f, a gear housing 32, a plate 31r and a rear bearing housing 30r, portions of which are shown in Fig. 20. These members are aligned by dowel pins 35 and they are fastened together by studs 36 threaded into housing 30f and receiving nuts 37 which appear also in Fig. 19.

Housings 30f and 30r are surrounded by screens 40 and 42, respectively, the margins of which are clamped

as shown in Fig. 1A by rings 41 and 43, respectively, said rings being received by the flanges of housings 30f and 30r, respectively. A ring 44 secured to housing 30r retains screen 42. Screen 40 is retained between the left flange of housing 30f and the plate 31f. These screens serve to protect the pump during storage and handling but are not relied upon to filter the fluid which passes into and out of the pump. The liquid which enters the pump is filtered by forcing it through a 40 micron filter by means of an auxiliary pump which receives liquid from a booster gear pump submerged in the liquid contained in a supply reservoir. The liquid discharged from the disclosed pump may be filtered by a filter which is capable of retaining metal particles which may be dislodged from the pump.

Housings 30f and 30r support, respectively, drive shaft pressure pocket sleeves 50f and 50r and driven shaft pressure pocket sleeves 51f and 51r (Fig. 1). Sleeve 50f is shown in Figs. 21 and 22 on large scale and sleeve 51f in Figs. 23 and 24. Each of the housings 30f and 30r receives the stem 52 of a disc 53, the periphery of which is received by recesses 54 of the sleeves, as shown in Figs. 21—24. The disc 53 locates the sleeves 50f and 50r and 51f and 51r in certain angular positions and prevents rotation of these sleeves with respect to the housings.

Referring to Figs. 21 and 22, sleeve 50f is longitudinally grooved to provide pockets Af, Bf, Cf and Df. Referring to Figs. 23 and 24, sleeve 51f is longitudinally grooved to provide pockets Af', Bf', Cf' and Df'. Before

these pockets are formed, the interior cylindrical surfaces of the sleeves indicated at 55 in Figs. 22 and 24 and the shoulder portions 56 are coated with a uniform layer 57 of babbitt permanently bonded to the sleeves. The grooving of the sleeves to form these pockets leaves babbitt 59 bonded to the internal cylindrical surfaces thereof. The ends of these pockets are closed by rings 58 having layers of babbitt 59 bonded to the internal cylindrical surfaces thereof. The rings 58 are forced into annular recesses provided by the sleeves.

As shown in Fig. 1, sleeves 50f and 50r and 51f and 51r, respectively, receive a drive shaft 60 and a driven shaft 61. These shafts are supported by similar ball bearings 62, the outer races of which are received between nuts 63 and rings 64.

As shown in Figure 1B, ring 64 is engaged by an annular seal housing 65 which contains ring 66 of resilient

material and a contiguous seal ring or washer 67. Housing 65 engages a seal ring 68 of resilient material retained in an annular groove provided by housing 30f or 30r. A spring washer 69 engages ring 67 which compresses seal ring 66 against housing 65 and a sleeve 70 and also urges housing 65 against ring 64. Carbon ring 71 is pressed into sleeve 70. Spring washer 69 urges assembly of sleeve 70 and ring 71 against a lapped surface on ring 73 which is pressed on both ends of shafts 60 and 61. The seal assemblies are indicated in Fig. 1 by numeral 75 and these seals operate to resist leakage of liquid to the left of the sleeves 50f and 51f and to the right of the sleeves 50r and 51r. These seal assemblies are purchased parts.

Referring to Figs. 10 and 11, shafts 60 and 61 provide meshing, helical gears 80 and 81, respectively, which, as shown in Figs. 10 and 11, rotate, respectively, clockwise and counterclockwise. The end thrust produced by the helical gears on the shafts 60 and 61 is taken up by the bearings 62. The gears 80 and 81 are enclosed by arcuate layers 82 of babbitt bonded to housing 32 and also by layers 83 of babbitt bonded to cylindrical plates 31f and 31r (Fig. 1). The right end faces of gears 80 and 81 are held closely with respect to the babbitt layer 83 of plate 31r with a small clearance determined by adjustment of left nuts 63. The babbitt layer 83 of plate 31f is held closely with respect to the left end faces of gears 80 and 81 with a small clearance determined by the adjustment of nuts 63 (Fig. 2). Thus the gears 80 and 81 fit closely between layers 83. A function of the layers 83 is to pick up small particles of foreign matter which had passed the 40 micron filter and which became embedded in these layers.

The liquid enters the pump through screen 42 and thence through duct 84 (Fig. 2). The rotating gear teeth pick up this fluid and force it through outlet duct 85 and screen 40.

A mounting member 100 which is shown diagrammatically in cross section in Fig. 25 provides an annular pump receiving recess which includes chambers 101 and 102 surrounding the screens 42 and 40, respectively; and these chambers are separated by a gear housing flange 103 which is sealed with respect to the member 100 by a seal ring 104 received by an annular groove 86 (Fig. 1) of the gear housing. Chamber 101 receives liquid under relatively low pressure which flows through a duct 105 from the outlet of a booster pump; and chamber 102 discharges liquid under relatively high pressure through a duct 106.

Referring to Figs. 19-24, sleeves 50r (Fig. 19) and 50f (Fig. 21) have, respectively, pressure fluid receiving pockets Ar, Br, Cr and Dr and Af, Bf, Cf and Df, which are, respectively, equal in area and which are spaced by babbitt lined sealing segments I, II, III and IV. Sleeves 51r and 51f have, respectively, pressure fluid receiving pockets Ar', Br', Cr', Dr' and Af', Bf', Cf', Df' which are, respectively, equal in area and which are spaced by babbitt lined sealing segments I, II, III and IV.

Pocket Af of sleeve 50f (Fig. 21) is connected by duct a1 with annular groove a2 of housing 30f (Fig. 1). Annular groove a2 communicates with a notch aN (Figs. 8 and 4) in housing 30f connected by a duct a3 (Fig. 15) communicating with the pump inlet passage 84 (Figs. 10, 11 and 15) whereby the pocket Af is subjected to the pressure of the liquid entering the pump.

Pocket Bf of sleeve 50f (Fig. 21) is connected by duct b1 with annular groove b2 (Fig. 1) of housing 30f connected with duct b3 which appears in Figs. 4, 7, 10 and 11.

Pocket Cf of sleeve 50f (Fig. 21) is connected by duct c1 with annular groove c2 of housing 30f (Fig. 1) connected as shown in Fig. 5 with duct c3 which appears in Figs. 4 and 10.

Pocket Df of sleeve 50f (Fig. 21) is connected by duct d1 with annular groove d2 (Fig. 1) of housing 30f 75

which is connected, as shown in Fig. 4, by duct d3 with pump outlet duct 85.

Pocket Af' of sleeve 51f (Fig. 23) is connected by duct a1' with annular groove a2' of housing 30f (Fig. 1) which connects with notch aN (Figs. 8 and 4) connected by duct a3 with pump inlet duct 84, as shown in Figs. 10 and 11.

Pocket Bf' of sleeve 51f (Fig. 23) is connected by duct b1' with an annular groove b2' of housing 30f (Fig. 1) which, as shown in Fig. 7, is connected with duct b3', the end of which appears in Figs. 4, 10 and 11.

Pocket Cf' of sleeve 51f (Fig. 23) is connected by duct c1' with annular groove c2' of housing 30f (Fig. 1) which is connected, as shown in Fig. 5, with duct c3' appearing in Figs. 4, 10 and 11.

Pocket Df' of sleeve 51f (Fig. 23) is connected by duct d1' with annular groove d2' of housing 30f (Fig. 1) which is connected, as shown in Fig. 4, by duct d3' with pump outlet duct 85.

Pocket Ar of sleeve 50r (Fig. 19) is connected with annular groove a2 of housing 30r (Fig. 1) which is connected, as shown in Fig. 9, by duct a3 of housing 30r with pump inlet 84.

Pocket Ar' of sleeve 51r (Fig. 19) is connected with annular groove a2' of housing 30r (Fig. 9) connected by duct a3' with pump inlet 84.

Pocket Br of sleeve 50r (Fig. 19) is connected with annular groove b2 of housing 30r (Fig. 1) which is connected, as shown in Fig. 7, with duct b3 of housing 30r which appears in Fig. 3.

Pocket Br' of sleeve 51r is connected with groove b2' of housing 30r which is connected, as shown in Fig. 7, with duct b3' of housing 30r which appears in Fig. 3.

Pocket Cr of sleeve 50r (Fig. 19) is connected with annular groove c2 of housing 30r (Fig. 1) which is connected as shown in Fig. 5, with duct c3 of housing 30r which appears in Fig. 3.

Pocket Cr' of sleeve 51r is connected with groove c2' of housing 30r which is connected, as shown in Fig. 5, with duct c3' of housing 30r which appears in Fig. 3.

Pockets Dr and Dr' of sleeves 50r and 51r, respectively, are connected, respectively, with annular grooves d2 and d2' of housing 30r connected, respectively, with ducts d3 of housing 30r which appears in Fig. 3. Duct d3 of housing 30r is connected with the pump outlet 85.

If, for example, the pump is used to increase liquid pressure from 150 p. s. i. inlet pressure to 600 p. s. i. outlet pressure, the four A pockets receive liquid at 150 p. s. i. pressure and the four D pockets receive liquid at 600 p. s. i. pressure. The four C pockets receive liquid at pressure somewhat less than 600 p. s. i. and the four B pockets receive liquid at pressure between 150 p. s. i. and the pressure of the liquid at the C pockets. The locations of the pockets, the areas of the pockets and the unit liquid pressures at the pockets are such as substantially to balance out the forces to which the shafts are subjected by the gear tooth loading and the hydraulic loading of the pump. In other words, the bearings 62 of each shaft are subjected to the resultant of forces including those derived by gear tooth loading and hydraulic loading of the pump and to forces derived from the pressure pockets which surround the larger cylindrical portions of the shaft. The resultant of these forces is a force of relatively small magnitude applied radially of the shaft axis and varying in amount and in direction of force application. In the case of a gear pump constructed in accordance with the present invention to boost liquid pressure from 150 p. s. i. to 600 p. s. i., the value of this resultant is about 35 p. s. i. which the shaft bearings can withstand without appreciable wear for a long time.

Because side thrust of the shaft journals has been reduced to practically a negligible value, the shaft bearings can be relatively small in diameter in consequence of which the gear shafts can be relatively close together and a compact construction results.

While the embodiment of the present invention as herein disclosed, constitutes a preferred form, it is to be understood that other forms might be adopted.

What is claimed is as follows:

1. A gear pump for pressurizing a liquid comprising a gear housing having an inlet and an outlet, shaft bearings, parallel shafts supported by said shaft bearings and extending through the housing and providing meshing gears in the housing and each shaft having two cylindrical portions located at opposite sides of the meshing gears and adjacent thereto, four sleeves, respectively, receiving the cylindrical portions and each sleeve having a plurality, more than two, of liquid receiving pockets which are defined by longitudinally extending grooves closed at their ends and further closed by portions of the cylindrical portions of the shafts and spaced circumferentially by sealing segments on said sleeves having close clearance with said cylindrical portions, and means providing bearing supports and sleeve supports and ducts which connect the pockets of each sleeve respectively with regions of the pump at which the liquid is at different pressures, the location of the pockets, the areas of the pockets and the unit liquid pressure at the pockets being such as substantially to balance out the forces to which the shaft bearings are subjected by the gear tooth loading and the hydraulic loading of the pump. 20

2. A gear pump according to claim 1 in which each sleeve has four liquid receiving pockets which are connected, respectively, with the pump inlet, the pump outlet and two different regions of the pump between the inlet and outlet. 30

3. A gear pump for pressurizing a liquid and comprising shaft bearings, parallel shafts supported by said shaft bearings and providing meshing gears and each shaft having two cylindrical portions located on opposite sides of the gear, sleeves respectively receiving the cylindrical portions, two housings each supporting two shaft bearings and two sleeves, a housing surrounding the gears and located between the sleeve housings, means for securing the three housings together, pump inlet and outlet passages provided by the gear housing, each sleeve having a plurality of liquid receiving pockets which are defined by longitudinally extending grooves closed at their ends and further closed by portions of the cylindrical portions and spaced circumferentially by sealing segments on said sleeves having close clearance with said cylindrical portions, and ducts provided by the sleeve and the sleeve housings for connecting the pockets of each sleeve respectively with regions of the pump at which the liquid is at different pressures. 40

4. A gear pump according to claim 3 in which the ducts associated with the pockets of each sleeve include spaced, internal annular grooves positioned in the sleeve

housing, holes provided by the sleeve for connecting its pockets respectively with the grooves of the sleeve housing and passageways provided by the sleeve housing for connecting the grooves respectively with regions of the pump at which the liquid is at different pressures.

5. A gear pump for pressurizing a liquid and comprising shaft bearings, parallel shafts supported by bearings and providing meshing gears and each shaft having two cylindrical portions located on opposite sides of the gear, sleeves respectively receiving the cylindrical portions, two housings each supporting two shaft bearings and two sleeves, a housing surrounding the gears and located between the sleeve housings, two plates each of which is located between a sleeve housing and the gear housing, means for securing the two plates and the three housings together, the interior of the gear housing and the sides of the plates adjacent thereto being lined with a relatively soft metal in which particles of foreign matter in the pressurized liquid can become embedded.

6. A gear pump for pressurizing a liquid having a supporting member, a cylindrical member received by a cylindrical recess in the supporting member and forming an enclosure, said enclosure comprising a middle or gear housing having cylindrical flanges, cylindrical plates respectively abutting the cylindrical flanges of the gear housing and cooperating therewith to enclose meshing gears, two end housings, each having cylindrical flanges, one flange of each end housing abutting a cylindrical plate, parallel shafts extending within the parts of the enclosure and providing meshing gears in the gear housing and between the plates, bearings supporting the shafts and supported by the end housings, pump inlet and outlet ducts provided by the adjacent flanges of the end housings, said ducts communicating respectively with the spaces between the flanges of the end housings, and a seal provided by the enclosure for cooperation with a wall of said recess of the supporting member to block flow of liquid between the spaces between the flanges of the end housings, the supporting member providing ducts communicating respectively with said spaces. 35
